US00D600753S

(12) United States Design Patent
Seo

(10) Patent No.: US D600,753 S
(45) Date of Patent:  Sep. 22, 2009

(54) WARNING STICKER FOR EXTENDED
BATTERY OF MOBILE ELECTRONIC PRODUCTS

(75) Inventor: Jin-Gyu Seo, Seoul (KR)

(73) Assignee: Samsung Electronics Co., Ltd.,
Suwon-Si (KR)

() Term: 14 Years

(21) Appl. No.: 29/329,390

(22) Filed: Dec. 15, 2008

(51) LOC (9) Cl. 19-08

(52) U.S. Cl. D20/25; D20/27

(58) Field of Classification Search D20/10,
D20/11, 13, 14, 22, 24, 25, 27-33, 40, 99;
